CLAIM

The ornamental design for a camera, as shown and described.

DESCRIPTION

FIG. 1 is a front top perspective view of a camera showing our new design;

FIG. 2 is a rear bottom perspective view of the camera shown in FIG. 1;

FIG. 3 is a front elevational view of the camera shown in FIG. 1.

FIG. 4 is a rear elevational view of the camera shown in FIG. 1;

FIG. 5 is a left-side elevational view of the camera shown in FIG. 1;

FIG. 6 is a right-side elevational view of the camera shown in FIG. 1;

FIG. 7 is a top plan view of the camera shown in FIG. 1; and, FIG. 8 is bottom plan view of the camera shown in FIG. 1. The broken lines shown in the drawings represent portions of the camera that form no part of the claimed design.
